UNITED STATES PATENT OFFICE.

HIRAM G. SEDGWICK, OF MILL VALLEY, CALIFORNIA.

ELECTRICAL TRAIN-STOP.

No. 852,631.

Specification of Letters Patent.

Patented May 7, 1907.

Application filed June 14, 1906. Serial No. 321,761.

To all whom it may concern:

Be it known that I, HIRAM G. SEDGWICK, a citizen of the United States of America, and a resident of Mill Valley, county of Marin, 5 State of California, have invented certain new and useful Improvements in Electrical Train-Stops, of which the following is a full and clear specification, reference being had to the accompanying drawings, in which—

10 Figure 1 is a diagram showing one section orb lock of a single track roadway; Fig. 2 a similar view showing a slightly modified arrangement; and Fig. 3 a side elevation showing the modified form of the stopping magnet and the magnetically-controlled train-stopping circuit on the locomotive or other vehicle of the train.

15 The object of this invention is to provide an extremely simple block system for preventing collisions, means being provided whereby each train as it proceeds preëmpts a block or section of the roadway, preventing any train coming from either direction from entering the block until it is free of trains, the 20 means for preventing trains from entering the block while thus preëmpted being entirely automatic and independent of all signals and the actions of the train-crews, as more fully hereinafter set forth.

25 In its preferred form this invention consists in dividing up the track into sections *a* constituting the blocks, the rails in these blocks being suitably bonded. Between the ends of each pair of adjacent blocks is arranged a 30 short rail section *b* insulated from the block sections proper. A portion, *a'*, of each end of each block section, as shown in Fig. 1, is made neutral by being insulated from main section *a* and the short section *b*.

35 Adjacent to the short section *b*, on each side of the track or roadbed is arranged a magnet *d*, which is in partial circuit with a suitable battery and with the short rail section *b* and the rails of one of the adjacent block sections *a*; that is to say, this magnet is in a circuit which is broken at two points, one break occurring between the main block rails and the other break between the short rail sections. In the drawing the magnet at 40 the right side of the roadbed is connected with the block rails ahead and the magnet of the other side is connected with the block rails next in the rear. The neutral rail sections *a'* are insulated from all circuits and 45 rails.

The locomotive or other vehicle of the train is provided, as shown in the diagram in Fig. 3, with a suitable circuit-closing device adapted to be actuated by magnetism. In the device shown an armature *c* is carried by a 50 spring-retracted arm *e*, in such position that as the train moves along the track it will pass close enough to the magnet to be drawn downwardly if the magnet be energized. When thus drawn downwardly a circuit *f* 55 will be closed in which circuit a suitable battery and a brake magnet will be included. Any other circuit-closing device may be employed, and it will be obvious also that the brake magnet may be adapted to operate 60 any suitable train-stopping mechanism, although I prefer that it be arranged to actuate a brake-pipe venting device.

There will be two of these circuit-closers on each train, one at each side thereof, and a 65 suitable switch will be arranged to automatically cut out one or the other of these circuits by the reversal of the reverse lever of the locomotive, so that the armature on the right side only of the train will be subjected 70 to the influence of the magnets on the roadbed.

Referring to Fig. 2, it will be observed that the construction is the same as Fig. 1 except that the neutral or inactive sections *a'* are 75 omitted. It will be observed that while a train is on the block rails the wheels and axles thereof serve to close the magnet circuit connected to each end of the block except at the point between the short rails *b*. 80 It will be seen, therefore, that should another train pass onto the short section at either end of the block, the circuit at the right hand side of that short section would be completed, thus energizing the magnet included 85 in that circuit. Thus energizing the magnet automatically actuates the armature carried on that side of the locomotive, completing the circuit on the locomotive and applying the brakes. This manner of completing the 90 circuits by means of two trains is shown in Fig. 2 where is illustrated one pair of wheels of each of the two trains approaching each other. In this instance it will be observed that the train on the short rails will be 95 stopped by the magnet at the right of the roadbed. It will thus be observed that it will be impossible for two trains to meet, either going in the same direction or in opposite directions, upon the same block.

The non-active sections a' , shown in Fig. 1, will preferably be each approximately as long as the longest trains, so that a train cannot extend from the short rails to the block rails and thus waste current. It will be observed that by this system I do away with all brushes on the locomotive and contacts on the roadbed, thus doing away with a source of great trouble.

10. It will be observed that instead of magnets I may employ suitable induction coils on the roadbed in which case a suitable deflecting needle or another induction coil may be mounted on the locomotive to close the brake magnet circuit as the needle or coil passes through the field of the roadbed coil; it will be understood, therefore, that whenever I employ the term magnet in the claims this term will have this broader significance.
15. 20. What I claim and desire to secure by Letters Patent is:—

1. In a train-stopping block system, the combination of the main block rails suitably bonded, an insulated short rail section between the adjacent ends of each main block, a magnet adjacent to each short rail section, and a partial circuit including a battery and said magnet at each short rail section, this circuit being connected at one end to one of 25 the adjacent block sections and at the other end to the short rail section, for the purpose set forth.

2. In combination, a series of main block rails suitably bonded, an insulated short rail section between the ends of each adjacent block rail sections, a magnetic device on the roadbed at each side of each short rail section, and a partial circuit for each magnetic device, said circuit including a battery and 30

having its terminals at one end connected to the adjacent short rail section and the terminals at the other end connected to the adjacent end of one of the block sections, for the purpose set forth.

3. In a block system of the type set forth, 40 main block rails, short rail sections intermediate the main block rails, a neutral rail section between each short rail section and the adjacent main block rails, a magnetic device at either side of the roadway adjacent to each 45 short rail section, and a partial circuit for each magnetic device, said circuit including a battery and connected at one end to the short rail section and at its other end to the adjacent end of one of the block sections.

4. In a train-stopping block system, a series of rail blocks having an insulated short rail section between them, a magnetic stopping device adjacent each of said short rail sections, this magnetic device being included 50 in a partial circuit one branch of which is connected to the adjacent insulated short rail section and the other branch of which is connected to the adjacent right hand rail of the next block ahead, the remainder of said circuit having included in it a battery and having one end connected to the left hand rail of the block ahead and its other end connected to the opposite short rail section, substantially as and for the purpose set forth.

In testimony whereof I hereunto affix my signature in the presence of two witnesses this 3rd day of April 1906.

HIRAM G. SEDGWICK.
